UNITED STATES PATENT OFFICE.

JOSEPH LUTHER HART, OF CHICKASHA, OKLAHOMA.

ENGINE.

1,222,863.

Specification of Letters Patent. Patented Apr. 17, 1917.

Application filed July 7, 1915. Serial No. 38,602.

To all whom it may concern:

Be it known that I, JOSEPH L. HART, a citizen of the United States, and a resident of Chickasha, in the county of Grady and State of Oklahoma, have invented certain new and useful Improvements in Engines, of which the following is a specification.

My invention is an improvement in engines, and has for its object to provide a simple, compact and durable engine of the fluid pressure operated type, wherein stuffing boxes, eccentric rods and the like are dispensed with, the supply of fluid to the engine and the exhaust being controlled by the pressure in the cylinder.

In the drawings:

Figure 1 is a longitudinal vertical section; Fig. 2 is an end view;

Fig. 3 is a top plan view of the piston rod;

Fig. 4 is a top plan view of the slide valve;

Fig. 5 is an end view of Fig. 4;

Fig. 6 is a side view of the valve stem;

Fig. 7 is a side view of a modified form; and

Fig. 8 is a longitudinal vertical section of the same.

In the embodiment of the invention shown in Figs. 1 to 6, the cylinder 1 is provided with a base 2, and heads 3 and 3^a are secured to the ends of the cylinder, by means of bolts and nuts 4. The bolts are passed through marginal flanges 5 at the respective ends of the cylinder, and the bolts are engaged by the nuts on the inner side of the flanges 5.

It will be noted from an inspection of Fig. 1 that the heads are rabbeted on their inner faces and at their edges, as indicated at 7, to receive the packing rings.

Each of the heads 3 and 3^a is provided with a cylindrical chamber or extension 8 and 8^a, respectively, the said chambers being coaxial with the heads and with the cylinder, and extending outwardly from the centers of the heads. The cylinder has a diaphragm 9 at its center, and of considerable thickness, as shown, and this diaphragm is provided with a central opening 10, having at each end a marginal rib 11.

The piston rod 12 is mounted to move in the opening 10 of the diaphragm, and the said rod, as shown more particularly in Fig. 3, has a pair of parallel continuous peripheral ribs 13 at its center, the ribs being spaced apart from each other as shown, longitudinally of the rod.

The diaphragm 9 of the cylinder provides

for a chamber at each side of the diaphragm, and it will be noted from an inspection of Fig. 1, that this diaphragm is nearer the head 3 than the head 3^a, so that the chamber between the diaphragm and the head 3^a is of greater capacity than the chamber between the diaphragm and the head 3. Pistons 14 and 14^a are secured to the rod in their respective chambers, the piston 14 being adjacent to the head 3, while the piston 14^a is adjacent to the head 3^a.

The rod 12 is reduced and externally threaded at each end as indicated at 15, for receiving the heads 14 and 14^a, the said heads having central internally threaded openings which are engaged with its portions 15. Beyond each portion 15 the rod is provided with a second reduced externally threaded portion 16 for receiving a holding nut 17, to lock the adjacent piston in place. Beyond the threaded portion 16 the rod is provided at each end with a cylindrical extension 18, and heads 19 and 19^a are connected with the extensions, the heads 19 and 19^a fitting within the chambers 8 and 8^a of the heads 3 and 3^a.

The outer end of each of the extensions 18 is reduced and externally threaded as at 20, and the heads 19 and 19^a have internally threaded central openings which are fitted onto the heads. The heads are locked in place by set screws 21, each of which is engaged with an axial opening in the end of the adjacent extension 18.

The cylinder is provided with a valve chamber 22 of cylindrical form above the same, and at approximately the center of the cylinder, and the ends of the chamber are internally threaded and engaged by 95 threaded plugs or heads 23. A slide valve 24 is mounted for longitudinal sliding movement in the chamber 22, and the said valve has on its upper side a pair of parallel longitudinally extending ribs 25, for engagement by the valve stem 26 shown in Fig. 6. This stem is annularly reduced at its center, as indicated at 27, and the reduced portion fits between the ribs 25.

Annular shoulders formed at each end of the reduced portion engage the ends of the ribs, to prevent movement longitudinally of the stem on the part of the valve. Each end of the stem is reduced and threaded, as shown at 28, and these threaded portions engage internally threaded central openings in piston heads 29 and 29^a, the said heads

being arranged at the ends of the rod. The heads fit the valve chamber 22, and the said heads, the pistons 14 and 14^a, and the heads 19 and 19^a are provided with the usual packing rings.

Ports 30 and 30^a are provided for placing the chambers of the cylinder 1 in communication with the valve chamber. These ports are in the diaphragm 9, each port inclining 10 upwardly toward the valve chamber as shown, and the top of the cylinder is flattened at the ports, as shown at 31, to provide a bed upon which the slide valve may move.

It will be noticed from an inspection of 15 Fig. 1, that the under face of the valve is recessed as shown at 32, and the valve chamber has an exhaust 33 at the bed 31, and between the ports 30 and 30^a. The recessed portion of the valve 24 is of sufficient length 20 to connect either port 30 or 30^a with the port 33, as clearly shown in Fig. 1.

Pipes 34 and 34^a are provided for connecting the opposite ends of the cylinder, or the chambers of the cylinder with the opposite ends of the valve chamber 22. The pipe 34 leads from the cylinder at a point adjacent to the head 3, the said pipe extending upwardly from the cylinder and then longitudinally of the cylinder, and then downwardly and inwardly and engaging an axial opening in the head 23, adjacent to the head 3^a. The pipe 34^a opens from the cylinder adjacent to the head 3^a, and extends toward the opposite end of the valve chamber, being 35 connected to a central opening in the head 23 adjacent to the head 3 of the cylinder.

It will be noted from an inspection of 40 Fig. 1, that each of the pipes 34 and 34^a opens into the cylinder 1 at a point spaced apart far enough from the adjacent head 3 or 3^a, as the case may be, to prevent closing of the inlet end of the said pipe when the piston 14 or 14^a is at the end of its travel in that direction.

45 The chambers 8 and 8^a are water cylinders, and each of these chambers has a port at its outer end, which is connected to a tubular frame, by means of a nipple 35. The tubular frame is formed of pipes, consisting 50 of longitudinally extending pipes 36 and 36^a arranged above and below the cylinder, respectively, and vertical pipes 37 and 37^a, arranged at the opposite ends of the engine, and connecting the pipes 36 and 36^a.

55 An exhaust pipe 38 is connected with the pipe 36 intermediate the ends thereof, and check valves 39 are interposed in the length of the pipe 36 on opposite sides of the pipe 38. A supply or inlet pipe 40 is connected 60 with the pipe 36^a, intermediate the ends thereof.

A drainage exhaust pipe 41 is arranged below the cylinder, one end of the said pipe being threaded into an opening in the head 65 3 below the chamber 8, and a branch 42 leads

from the said pipe 41 to a port in the head 3^a. This pipe 41 is bent upward and then inward at its inner end to engage the port of the head 3, and the branch 42 extends upward and then inward into engagement 70 with the head of the port 3^a.

A steam supply pipe 43 leads from a suitable source of steam supply to the valve chest 22, opening at the center thereof, and between the ports 30 and 30^a. The pipe 40 75 is connected with a suitable source of water supply and it will be evident that when the double piston 14—14^a is reciprocated in the cylinder the heads 19, which are in fact plungers, will alternately draw water into the chambers 8 and discharge it therefrom. The discharged water passes by way of the pipes 37—37^a, 36 and 38 to the place of discharge, and the check valves 39 prevent the return of the water from the pipe 38.

In operation, with the parts in the position of Fig. 1, the steam entering the valve chamber through the supply pipe 43 will pass by way of the port 30 to the chamber between the diaphragm and the head 3, and the piston constituted by the rod 12 and the heads 14 and 14^a will be moved toward the head 3. Meanwhile, that portion of the chamber between the head 14^a and the diaphragm will be connected with the exhaust 95 33 by the slide valve 24. This valve is at this time in position to connect the port 30^a with the exhaust 33. At the same time the steam passes by way of the port 30, and the pipe 34 to that end of the valve adjacent to the head 29^a.

The opposite end of the valve chest, that is, the end adjacent to the head 29, is connected to that end of the cylinder adjacent to the head 3^a by the pipe 34^a. The steam entering the valve chest through the pipe 34 will move the valve toward the opposite end of the valve chest, thus connecting the port 30 with the exhaust and the port 30^a with the source of steam supply. As the piston 12—14—14^a reaches the end of its movement to the right of Fig. 1, the steam from the port 30^a will enter the pipe 34^a and will pass to that end of the valve chest adjacent to the head 29 and drive the valve to the right of Fig. 1. The exhaust steam between the head 29^a and the adjacent end of the valve chest will pass out through the pipe 34 into that end of the cylinder adjacent to the head 3, and since this steam will 110 be between the heads 14 and 19, it will leave the cylinder by way of the drain pipe 41.

With the parts in the position of Fig. 1, the exhaust steam between the head 29 and the adjacent end of the valve chest will pass 115 through the pipe 34^a to that portion of the cylinder between the piston 14^a and the head 3^a, and thence the steam may pass by way of the drain pipe 42 to the atmosphere.

Because of the coöperating pressures, the 120 130

valve 26—29—29^a will be moved toward the head 3 of the cylinder 1, placing the port 30 in communication with the steam supply pipe 43. Thus the piston 12—14—14^a will be reciprocated in the cylinder 1 and every time the piston moves in one direction, the valve 26—29—29^a will be moved in the opposite direction. For every movement of the piston the plungers 19 and 19^a will operate, one plunger forcing the water out of the adjacent chamber, while the other draws the water in. It is obvious that any fluid under pressure, as for instance, compressed air, might be used to operate the improved engine.

In the embodiment of the invention shown in Figs. 7 and 8, the cylinder 44 is supported by a suitable base 45, and the crank shaft 46 is supported at the opposite end of the base from the cylinder. The crank shaft has the usual fly wheel 47, and a disk 48 is secured to the shaft, the disk having a wrist pin 49. One end of a link 50 is journaled on the wrist pin, and the other end is connected with a cross head 51, which is mounted to move in cross head guides 52 extending longitudinally from the cylinder 44.

That end of the cylinder adjacent to the crank shaft is open, and the other end is closed by a head 53 which is secured to a marginal flange 54 on the adjacent end of the cylinder by means of bolts and nuts 55, and a gasket or packing ring 56 is arranged between the head and the plunger. The cylinder is provided with a diaphragm 57 at approximately its center, the diaphragm having a central opening 58, which is provided at each end with a marginal rib 59.

The piston rod 60 has the annular ribs 61 corresponding with the ribs 13 of Fig. 1, and the piston 62 corresponds to the pistons 14 and 14^a of Fig. 1 and are connected with the ends of the rod in the same manner as the heads 14 and 14^a, being held in place by lock nuts 63. The rod 60 is provided at the ends adjacent to the crank shaft with a cylindrical extension 64, and to this extension is connected a head 65, the head being held in place by a nut 66, and the head is rigid with the cross head.

The diaphragm 57 has inclined ports 67 and 67^a corresponding to the ports 30 and 30^a of Fig. 1, and these ports open into a valve chamber 68, upon opposite sides of a central exhaust port 70 for the chamber. The ends of the chamber are closed by heads 71 having threaded engagement with the ends of the chamber, and a slide valve 72 similar to the valve 24 of Fig. 1 is mounted to slide in the chamber, on a bed 73. This valve is connected to a valve stem 74 similar to the stem 26, and heads 75 are connected with the opposite ends of the stem.

Pipes 76 and 76^a connect the respective ends of the cylinder 45 with the opposite

ends of the valve chamber 68, the pipes 76 and 76^a corresponding in arrangement to the arrangement of the pipes 34 and 34^a. Steam is supplied to the valve chamber by a steam supply pipe 77, and a drainage pipe 78 is provided, this pipe having branches 79 which connect with the cylinder at the bottom thereof, and on opposite sides of the diaphragm.

An exhaust pipe 80 is connected with the 75 exhaust port 70, and pins 81 and 81^a are mounted to slide in the respective heads 71 of the valve chamber. A centrifugal governor 82 of the ball type is mounted on the supply pipe for the valve chest, and this 80 governor is connected to a moving part of the engine in order that the governor may be operated when the engine is running.

The operation of the embodiment just described is as follows:

With the parts in the position shown in Fig. 8, the steam from the supply pipe 77 will pass into that portion of the cylinder between the diaphragm 57 and the crank shaft, moving the piston constituted by the 90 rod 60 and the heads 62 toward the crank shaft. As the piston reaches the end of its stroke toward the crank shaft, the steam in that end of the cylinder adjacent to the crank shaft may pass by way of the pipe 76 95 to the valve chest at the end adjacent to the pin 81^a, and the valve will be driven toward the crank shaft. That end of the valve chest adjacent to the crank shaft is meanwhile in communication with the atmosphere 100 by way of the pipe 75, that end of the cylinder adjacent to the head 53, and the drain pipe 79.

Whenever the valve 72 is shifted to connect one port 67 or 67^a with the exhaust, the 105 other port is connected with the supply for the motive fluid. The governor 82 controls the supply of steam to the cylinder, and the engine may be reversed by means of the pins 81 and 81^a. By cutting off the steam, when 110 the engine is stopped, the valve may be moved in either direction by means of the pins 81 and 81^a.

With the parts in the position shown in Fig. 8, and the steam cut off, the valve may 115 be moved toward the pin 81 by pressing inward on the pin 81^a. It will be noted that these pins have heads at their inner ends which are received in recesses or counterbores in the adjacent heads. Each compartment of the cylinder is also provided with a drainage valve indicated at 42^a.

In either embodiment the steam is the motive power that moves the valve, and the engine is self-contained and automatic in its 125 operation. As each end of the valve chest in Fig. 1 is connected with the source of steam supply, and this takes place at the end of the movement of the piston in each direction, the opposite end will be connected with the 130

atmosphere by way of the drain pipe 41 or 42. Drain valves 42^a are provided for draining the cylinder.

I claim:

5. 1. An engine comprising a cylinder having a transverse diaphragm provided with an axial opening, and dividing the interior of the cylinder into compartments, and having a valve chest at the diaphragm, and 10 ports leading from the several compartments of the cylinder to the chest, the chest having an inlet port and an exhaust port between the first named ports, a piston in the cylinder comprising a rod passing 15 through the opening in the diaphragm, and heads at the ends of the rod fitting the respective compartments, a valve in the valve chest, said valve being slidable in the chest in opposite directions to alternately connect 20 the ports of the compartments with the inlet and exhaust, means for transmitting the pressure from each compartment to the opposite end of the valve chest to move the valve, and a pump connected with each end 25 of the piston and operated thereby.
2. An engine comprising a cylinder having a transverse diaphragm provided with an axial opening, and dividing the interior of the cylinder into compartments, and having a valve chest at the diaphragm, and 30 ports leading from the several compartments of the cylinder to the chest, the chest having an inlet port and an exhaust port between the first named ports, a piston in the cylinder comprising a rod passing through 35 the opening in the diaphragm, and heads at the ends of the rod fitting the respective compartments, a valve in the valve chest, said valve being slidable in the chest in op-

posite directions to alternately connect the 40 ports of the compartments with the inlet and exhaust, and means for transmitting the pressure from each compartment to the opposite 45 end of the valve chest to move the valve.

3. In an engine, a cylinder having a diaphragm provided with an opening, and dividing the cylinder into compartments, a valve chest at the diaphragm having an inlet and an exhaust port, the compartments 50 having ports leading to the chest, a piston in the cylinder, and comprising a rod passing through the opening of the diaphragm, and provided with heads fitting the compartments, a valve slidable in the chest, and adapted to alternately connect the ports of the compartments with the inlet and exhaust, and means for transmitting the pressure from each compartment to the opposite 55 ends of the valve chest to move the valve.

4. An engine comprising a cylinder having a diaphragm dividing the cylinder into compartments, a piston comprising a head in each compartment and rigidly connected with each other, the cylinder having a valve 60 chest, and ports leading from the chest to the compartments at the diaphragm, said chest having an inlet and an exhaust port, a valve slidable in the chest for alternately 65 connecting the ports of the compartments to the inlet and exhaust, and means for transmitting pressure from each compartment to the opposite ends of the valve chest to move the valve.
